UNITED STATES PATENT OFFICE.

CHARLES H. BEELER, JR., OF PHILADELPHIA, PENNSYLVANIA, ASSIGNOR TO
THE AMERICAN TYPE FOUNDERS COMPANY, OF NEWARK, NEW JERSEY.

DESIGN FOR A FONT OF TYPE.

SPECIFICATION forming part of Design No. 24,684, dated September 17, 1895.

Application filed December 22, 1893. Serial No. 494,468. Term of patent 7 years.

To all whom it may concern:

Be it known that I, CHARLES H. BEELER,
U.S., a citizen of the United States, residing in
Philadelphia, Pennsylvania, have invented a
certain Design for Type, of which the following
is a specification.

My design is clearly shown in the accompa-
nying typographical impression, which illus-
trates the upper-case letters, the lower-case
letters, and the numerals.

The main feature of the design is the pec-
uliar effect given to the type by the straight
head-line and the irregular base-line. A num-
ber of the characters of the upper case extend
below the base-line and the lines of a number
of the letters are tapered and terminate in
enlarged ends. For instance, the right-hand
lines of the letters A, H, K, M, and R are ta-
pered and inclined and slightly curved, ex-

tending below the base-line; the lower por- 20
tion of each letter C, F, G, J, P, and T also
extends below the base-line and terminates in
a curved enlargement, and the lower bars of
the letters E, L, and Z are inclined and ex-
tend below the line. 25

The lower-case letters and numerals are in
keeping with the upper-case letters.

I claim—

The design for a font of type as herein de-
scribed and shown in the accompanying typo- 30
graphical impression.

In testimony whereof I have signed my
name to this specification in the presence of
two subscribing witnesses.

CHARLES H. BEELER, JR.
